SELF-CLOSING MEASURING VALVE

James Fraser, Edge Moor, Del., assignor to
Speakman Company, Wilmington, Del., a cor-
poration of Delaware

Application July 2, 1938, Serial No. 217,152

3 Claims. (Cl. 251—138)

The general object of the present invention is to provide an improved self-closing measuring valve structure primarily devised and adapted for use as a lavatory supply valve, and characterized by its mechanical simplicity and effectiveness, and by its quiet and effective operation, and by the ease and accuracy with which it may be adjusted to vary the amount of water discharged by the valve on each normal actuation thereof.

The various features of novelty which characterize my invention are pointed out with particularity in the claims annexed to and forming a part of this specification. For a better understanding of the invention, however, its advantages and specific objects attained with its use, reference should be had to the accompanying drawing and descriptive matter in which I have illustrated a preferred embodiment of the invention.

Of the drawing:

Fig. 1 is a longitudinal section of a lavatory supply valve;

Fig. 2 is a section on the line 2—2 of Fig. 1.

In the drawing, I have illustrated the use of my invention in an ordinary basin supply faucet, comprising a casing element A, having a lower inlet chamber A' adapted to receive water at one end from a supply pipe B, and having an upper outlet chamber A², with a lateral discharge spout A³ leading away from the chamber A². The casing element A is formed with an internal annular shoulder A⁴ between its inlet and outlet chambers A' and A², and against which the inner lower end of a tubular valve guide and seat member C is normally clamped. The member C extends through an internally threaded opening A⁵ in the top wall of the casing element A, and is in threaded engagement therewith. As shown, a gasket or washer A⁶ is interposed between the shoulder A⁴ and an annular flange portion of the member C, in abutting relation with said shoulder. The bore of the tubular member C comprises an upper plunger chamber portion C', separated by a gasket or packing C² from a lower water chamber portion C³. Water may enter the chamber C³ at its lower end through an axial port C⁴, and passes from the chamber C' through lateral ports C⁵ into the casing outlet chamber A².

The flow of water from the casing inlet chamber A' through the port C⁴ to the outlet chamber A², is controlled by an axially movable valve member E, which in its normally closed position seats against a valve seat washer D, coaxial with the port C⁴, and clamped against the lower end

of the valve member C at the margin of said port. The valve member E is secured to the lower end of a coaxial valve stem E', which extends through chambers C³ and packing C², and has its outer end secured to a plunger element F which extends into the plunger chamber C' through the open upper end of the latter.

The plunger F is externally threaded, and is screwed into an internally threaded socket formed in a push button member G of inverted cup shape, and having a lower rim or skirt portion G' which is adapted to surround, and be in telescopic relation with the upper portion of the wall of the chamber C'. Rotation of the member G relative to the plunger F, effects their relative adjustment in the direction of the length of the plunger, and thereby determines the extent of opening movement which can be given the valve member E, said extent being directly dependent on the distance between the upper end of the member C and the annular internal shoulder G², extending inwardly from the outer end of the skirt portion G' of the member G, or, as shown, by the distance between the member C and the washer G³ forming a facing for said shoulder, and preferably formed of some suitable non-metallic material to avoid the generation of noise when moved into engagement with the member C.

To permit the parts F and G to be readily adjusted relative to one another and to be secured in any particular adjustment, the member G is formed with a lateral threaded opening receiving a set screw G⁴ which may be screwed into clamping engagement with the member F. The latter is in splined relation with the member C, a pin H being shown as secured to and extending radially away from the member F, into a guide groove C⁷ formed in the inner wall of the plunger chamber C'.

A spring I, acting between the packing C² and the plunger F, biases the valve E' for movement into its closed position. The time required for movement of the valve E from its wide open to its fully closed position is regulated by timing means comprising a hollow element J formed with a piston chamber J' coaxial with and beneath the member C, and having an enlarged upper end extension internally threaded to receive a short externally threaded lower end portion of the member C and thereby detachably connect the parts C and J. The cylindrical body portion of the element J is formed with lateral ports J² adjacent its upper end through which water may pass to the port C⁴ and thence to the

- outlet chamber A², when the valve member E is out of its closed position. The lower end of the piston chamber J' in the member J is closed except for an axial port J³ of small diameter.
- 5 The speed of the closing movements of the valve member E are controlled by a timing or dashpot piston, which comprises a cup part K of leather, having its body, or cup bottom portion, clamped against the lower end of the valve member E, 10 by a clamping member L, into which the lower end portion of the valve stem E' is threaded.

The members E and L are somewhat smaller in diameter than the piston chamber J', and the cylindrical portion of the piston cup leather may 15 move inwardly enough to permit water to pass freely upward past the piston from the lower end of the timing cylinder J', on the opening down movement of the valve E, so as to not significantly impede that movement. As the 20 valve E moves in the closing direction under the action of its bias spring I, however, the cup leather K expands into close contact with the cylindrical wall of the chamber J', and prevents flow of water downward past the cup leather washer into the lower end of timing chamber J'. 25 In consequence, the rate of the up, or closing, movement of the valve E, is dependent upon the definite time period required for the piston chamber J' to fill with water through the restricted orifice J³.

The clamping member L is provided with an axial extension in the form of a rod L' slightly smaller in diameter than the passage J³, which extends into the latter, so that the orifice J³ is 30 subjected to a cleaning action on each valve movement. As shown, the member J is formed with a chamber J⁴ beneath, coaxial with, and larger in diameter than the port J³, and communicating at its lower end with the inlet chamber A', through a screen J⁵, which prevents foreign bodies in the water from passing into the restricted port J³.

In the preceding description, I have used the terms "upper" and "lower" to describe the relative 45 location of the parts, when the valve mechanism is vertically disposed as shown in the drawing, and as is usual, but those skilled in the art will understand that the use of the invention does not require the valve mechanism to be vertically 50 disposed.

In the construction shown, all of the valve mechanism parts are mounted in or attached to the seat and guide member C and collectively form a valve mechanism unit which may be bodily 55 mounted in the casing element and removed therefrom. To facilitate the removal of the unit, the member C has a portion C⁶ shaped for engagement by a wrench employed to thread the member C into and out of engagement with the 60 threaded portion A⁵ of the casing element. When the unit is detached from the casing, its movable parts can be moved, and their operative condition determined in many cases, without disassembling the unit.

65 The valve mechanism shown is positive in operation, free from hammering or chattering, and the valve member E is adapted to seat tightly, and thus avoid drippage, and the restricted timing port J³ is effectively cleaned on each operation of 70 the valve. The advantages just referred to are obtained, moreover, with a construction which is relatively simple and compact, and which is characterized in particular by the ease and accuracy with which the extent of valve opening movement 75 may be adjusted so as to thereby vary the amount

of water discharged, on each normal operation of the valve.

The form and disposition of the push button member G, is especially advantageous because the skirt portion G' of the member extends over 5 and forms a cover for the joint between the plunger F and the wall of the chamber C' and thus forms a shield against the passage of dust or dirt into that joint and chamber. Furthermore, with the push button formed, and associated with 10 a member C formed as shown, the adjustment parts are made readily accessible, and are protected against contact with water, while at the same time the valve construction may be made compact and given a pleasing appearance. 15

Having now described my invention, what I claim as new and desire to secure by Letters Patent, is:

1. A self-closing, measuring basin supply faucet, comprising a casing element formed with a 20 lower inlet chamber, an upper outlet chamber, a chamber connecting portion, and a wall opening above said outlet chamber and a lateral discharge spout opening from said outlet chamber, and a valve mechanism unit removably mounted in said 25 element and comprising a member extending through said wall opening and across said outlet chamber and into said connecting portion, and forming a partition between said chambers with a valve controlled port therein, a valve movable 30 downward away from, and biased for movement upward into engagement with said member to thereby open and close respectively and having a valve stem extending upwardly through said member, a plunger telescopically movable in the 35 upper end portion of said member and connected to said valve stem, a push button mounted on and adjustable axially of said plunger to thereby regulate the extent of opening movement of the valve which is terminated by engagement of said 40 plunger and member, a hollow element detachably secured to said member and extending downwardly therefrom into said inlet chamber and comprising a timing chamber coaxial with said member and in free communication at its upper 45 end with said inlet chamber and with said port when said valve member is out of its closed position, and communicating with the inlet chamber through a straight restricted passage formed in the lower end portion of said element, and a 50 piston device connected to said valve and adapted to permit the relative free movement of liquid from the lower end of said timing chamber upward past said device on down movement of the valve, and to form a barrier to the flow of liquid 55 downward past said device into the lower end of said chamber on up movement of said valve.

2. A self-closing, measuring valve structure comprising a casing element formed with a lower inlet chamber, an upper outlet chamber and a 60 wall opening above said outlet chamber, and a valve mechanism unit removably mounted in said element and comprising a member extending through said wall opening and across said outlet chamber and into said inlet chamber, and forming a partition between said chambers with a valve controlled port therein, a valve movable 65 downward away from, and biased for movement upward into engagement with said member to thereby open and close, respectively, and having a 70 valve stem extending upwardly through said member, a plunger telescopically movable in the upper end portion of said member and connected to said valve stem, and comprising a lower skirt portion surrounding and spaced away from the 75

lower portion of the plunger and thereby providing an annular recess receiving the upper end of said member, non-metallic material mounted in the upper end of said recess in position to engage 5 said member when said push button is depressed to open the valve, a push button mounted on and adjustable axially of said plunger to thereby regulate the extent of the opening movement of the valve which is terminated by engagement of said 10 plunger and member, a hollow element secured to said member and extending downwardly therefrom into said inlet chamber and comprising a timing chamber coaxial with said member and in free communication at its upper end with said 15 inlet chamber and with said port when said valve member is out of its closed position, and communicating at its lower end with the inlet chamber

through a restricted passage, and a piston device connected to said valve and adapted to permit the relative free movement of liquid from the lower end of said timing chamber upward past said device on down movement of the valve, and to 5 form a barrier to the flow of liquid downward past said device into the lower end of said chamber on up movement of said valve.

3. A faucet as specified in claim 1, in which the restricted passage through which the timing chamber communicates with the inlet chamber, is an axial passage in the bottom wall of the timing chamber, and in which a passage cleaning pin secured to the valve extends into, but does not 10 fill said passage.

JAMES FRASER.
